UNITED STATES PATENT OFFICE.

CHRISTIAN F. HANSEN, OF NORFOLK, NEBRASKA.

METAL-CASTING DEVICE.

1,113,333.

Specification of Letters Patent.

Patented Oct. 13, 1914.

Application filed January 6, 1914. Serial No. 810,534.

To all whom it may concern:

Be it known that I, CHRISTIAN F. HANSEN, a citizen of the United States, and a resident of Norfolk, in the county of Madison and State of Nebraska, have invented certain new and useful Improvements in Metal-Casting Devices, of which the following is a specification.

This invention relates to metal-casting devices and more particularly to devices of this class employed for casting dental inlays and the like within molds produced by melting wax patterns which have been enclosed within investment cement.

15 In the practice of dentistry much difficulty has heretofore been experienced in producing perfect castings, due to the presence of air within the molds and the tendency of the molten metal to assume bead-like forms, which factors prevent the metal from completely filling the crevices and sharply-angled depressions of the cavity.

Various methods and means have been 25 presented which employ either vacuum or centrifugal force to introduce the metal into the mold. These means, however, are unreliable and cannot be depended upon to obviate the above-recited defects in casting.

30 The present invention has, therefore, for its primary object the production of an improved means for casting metal.

Another object of the invention is the 35 production of a thoroughly reliable device of this class employing both vacuum and centrifugal force.

Another object is the construction of a device of this class thoroughly efficient in operation yet inexpensive in production.

With these and other objects in view, the 40 invention, consisting in the construction, combination and novel arrangement of parts, will be fully understood from the following description, reference being had to the accompanying drawings, which form 45 a part of this application and in which like characters of reference indicate corresponding parts throughout the several views, of which,—

Figure 1 is a front elevation of a device 50 constructed in accordance with my invention; Fig. 2 is an enlarged longitudinal section of a portion of the mold-supporting arm and members associated therewith; Fig. 3 is a longitudinal section of the vacuum

drum; and Fig. 4 is a transverse section of 55 the same.

Although I have illustrated and herein described the preferred embodiment of my invention, I would not be understood as being limited to the specific structure chosen 60 for illustration, for without departing from the spirit and scope of the invention, various modifications and alterations of the arrangement of parts may be made.

The invention contemplates, broadly, a 65 device embodying a rotatable mold-carrying member, a vacuum chamber, means for rotating said mold-carrying member whereby the metal is thrown into the mold by centrifugal force, and means for exposing the 70 mold to the vacuum coincident with the rotation of the mold-carrying member whereby the air is withdrawn from the mold cavity and the vacuum coacts with centrifugal force in introducing the metal into 75 the cavity, all of which will presently be made clear.

Referring, now, to the illustrations, 5 is a standard having a flat base and upwardly-extending arms, 6, between which is mounted a drum, 7, which serves as the vacuum chamber and is carried by shafts, 8 and 9, journaled in bearings, 10, mounted upon the upper ends of the supporting arms. The shaft 9 is preferably hollow, communicates 80 with the interior of the chamber and carries upon its outer end a valve, 11, adapted for connection with a pump whereby the air may be withdrawn from the chamber. Upon the upper face of the drum (respecting normal position) is mounted a vacuum gage, 12. The peripheral wall of the drum is preferably thicker on one side to counter-balance the weight of the members normally depending from the opposite side, as will 85 later appear.

13 is an arm carried by the drum and having an axial bore, 14, which communicates at all times with the interior of the drum. Adjacent the outer end of the arm, 100 and preferably formed integrally therewith, is a cup, 15, adapted to carry the mold.

In practice the pattern is surrounded by a rather pervious investment, represented 105 at 16 and inclosed by an open-ended casing, 17, having walls slightly flared to coact with the similarly-shaped inner periphery of the

cup and thus make an air-tight connection. A minute passage, 18, communicates between the mold cavity, 19, and a conical depression, 20, in which the gold, or other metal, is to be melted.

It is essential that the cup 15 have valve-controlled communication with the vacuum, and for this purpose I reduce and thread the outer end of the arm to receive a valve 10 casing, 21, inclosing a valve, 22, having an angled stem, 23, encircled by a cap, 24, threaded upon the valve casing. The valve has an axial bore, 25, communicating with the bore 14 and intersected by a horizontal bore, 26, positioned to register with a tube, 27, interconnecting the mold receptacle and the valve casing. The drum 7 is rotated rapidly by any suitable means, as the pinion, 28, secured upon the shaft 8 and intermeshed with a relatively large spur-wheel, 29, having a handle, 30, and mounted for rotation upon a spindle, 31, extending from the standard.

To operate the device now disclosed, a 25 vacuum having been first created, the gold, or other mineral, is placed in the depression 20 and heat applied thereto. When the gold is thoroughly melted the drum is rotated rapidly whereupon the angled portion 30 of the valve-stem will be engaged by a fixed member, as the stud, 32, and thus cause the valve port 26 to register with the passage 27 whereby the mold cavity will be exposed to the vacuum.

Having thus described my invention, what I claim as new and desire to secure by Letters Patent of the United States, is,—

1. A device of the class described comprising a supporting means; a vacuum chamber; a rotatable element mounted upon said supporting means; a mold-carrying part carried by and disposed laterally to the rotatable element; a passage between the mold-carrying part and the vacuum chamber; 40 means for actuating said rotatable element; and a valve for controlling said passage, said valve being opened automatically coincidentally with the actuation of said rotatable element.

2. A device of the class described comprising a supporting means; a vacuum chamber rotatably-mounted thereon; a mold-carrying part carried by said vacuum chamber; a passage between said chamber and mold-carrying part; means for rotating said chamber whereby the metal will be thrown into the mold by centrifugal force; and a valve for the control of said passage, said valve being opened automatically coincidentally with the rotation of the vacuum chamber.

3. A device of the class described comprising a supporting means; a drum rotatably-mounted thereon; means for creating a vacuum within the drum; a mold-carrying part carried by the drum; a valve-controlled passage between the drum and mold-carrying part; and means for rotating the drum and thereby causing the molten metal to be thrown into the mold cavity by centrifugal force.

4. A device of the class described comprising a supporting means; a vacuum drum rotatably-mounted thereon; a mold-carrying part carried by the drum; means for rotating the drum; a passage between the drum and mold-carrying member; a valve for controlling said passage; and means for automatically opening said valve governed by rotation of the drum.

5. In a metal-casting device, a superstructure having a vacuum drum rotatably-mounted thereon and means for rotating the drum; a radial arm carried by the drum and having a bore communicating with the drum; a mold-carrying cup carried by the arm; a passage between said bore and cup; and a valve carried by the arm for controlling said passage; and means adapted for engagement with the valve whereby the valve is opened coincident with the actuation of said means for rotating the drum.

6. In a metal-casting device, a vacuum chamber; a rotatable element; a hollow arm carried thereby and disposed radially thereto, said arm communicating at all times with said vacuum chamber; a mold-receiving part carried by said arm; and a valve-controlled passage between said arm and mold-receiving part.

7. A vacuum chamber, a rotatable member and means for actuating said member, in combination with an arm carried by and disposed radially to said member; a mold-receiving part carried by said arm; a passage between said vacuum chamber and mold-receiving part; a valve for the control of said passage; and means for automatically opening said valve coincidently with the actuation of said rotatable member.

In testimony whereof I have hereunto set my hand in presence of two witnesses.

CHRISTIAN F. HANSEN.
